ATTORNEY

UNITED STATES PATENT OFFICE.

GEORGE N. HOFFMASTER, OF DOSTER, MICHIGAN.

PAVING-BLOCK.

1,262,048.

Specification of Letters Patent. Patented Apr. 9, 1918.

Application filed July 19, 1916. Serial No. 110,140.

To all whom it may concern:

Be it known that I, GEORGE N. HOFFMASTER, a citizen of the United States, residing at Doster, in the county of Barry and 5 State of Michigan, have invented certain new and useful Improvements in Paving-Blocks, of which the following is a specification.

This invention has relation to a method 10 and means for constructing road beds, and the nature and objects thereof will be readily apparent to those skilled in the art to which it appertains, in the light of the following explanation, of the accompanying 15 drawings, illustrating, what I now believe to be the preferred embodiment or mechanical expression of my invention, from among other forms and arrangements within the spirit thereof, or the scope of the appended 20 claims.

However, an object of the invention is to provide a road bed constructed mainly of concrete, placed *in situ*, or laid in the form of slabs, and of a width to accommodate a 25 single vehicle, thereby economizing in the use of material.

Another object of the invention is to provide a road bed of the character set forth, having a novel system of reinforcement, de- 30 signed to resist the strains to which a road bed constructed in this manner may be subjected.

A still further object of the invention is to provide in a road bed having the above 35 named characteristics, of a center camber extending longitudinally throughout the road bed for securing proper drainage and to form a joint between the lateral elements of the road bed, to permit expansion and 40 contraction of said elements, and for the purposes which will presently appear.

In addition to the foregoing, my invention comprehends improvements in the details of construction and arrangement of 45 parts, to be hereinafter described and particularly set forth in the appended claims.

In the accompanying drawings, in which similar and corresponding parts are designated by the same characters of reference, 50 throughout the several views in which they appear:

Figure 1, is a fragmentary view in plan of a portion of a road bed constructed in accordance with my invention.

55 Fig. 2, is a transverse section taken on the line 2—2 of Fig. 1.

Fig. 3, is a view in perspective of a slab forming a part of my improved road bed, and

Fig. 4, is a horizontal section taken on the 60 line 4—4 of Fig. 3.

With reference to the drawings, wherein I have illustrated several views of a completed road bed embodying my improvements and constructed in accordance with 65 my methods, 1 indicates two rows of connected slabs, placed end to end and spaced laterally from each other. In the improvement of a road bed by means of my methods, the old road bed indicated at 2 in Fig. 2, is 70 provided with a layer of sand 3, after the usual manner, and the slabs 1 are placed thereon as mentioned above.

Each slab is formed with, or provided 75 with longitudinal reinforcing bars 4, disposed adjacent the edges with the ends 5 of said rods projecting beyond one end of the slab, while the other ends 6 of said rods are entirely inclosed within the slab and provided with bent terminals extending toward 80 each other to permit the provision of recesses 7 formed in said end of the slab, in alinement with the rods and of a corresponding size, to receive the projecting ends of the reinforcing rods of an adjacent slab. 85 Each slab is further provided with transversely extending reinforcing rods 8 formed at one of their ends with eyes 9. The slabs are formed on their upper and lower surfaces adjacent their edges with semicircular 90 enlargements 10 defining when the slabs are in place, parallel spaced ridges on the surface of the road bed.

The slabs forming the spaced rows are disposed with their sides having the eyes in 95 opposition, with the rods 8 of opposed slabs in alinement, and the eyes connected by reinforcing rods 11 having angular terminals 12 which are received in said eyes. The space between the parallel rows of slabs 100 is next filled in with gravel or crushed rock as indicated at 13, and the upper surface 14 curved transversely so as to form a camber extending centrally and longitudinally throughout the length of the road bed, to 105 permit proper drainage. The rods 11 are thereby securely held in place and the transverse spaced relation of the rows of slabs maintained. Between the joints of mating slabs, a filling in of asphalt or the like indicated at 15 may be provided, spacing the 110 slabs slightly at the same time, and pro-

viding a waterproof joint, and permitting longitudinal expansion and contraction of the rows of slabs. The remote edges of the slabs may be filled in with gravel or crushed rock as at 16, to round off the edges of the road bed and provide a neat and uniform effect. The joints between mating slabs of each row may be disposed in relative staggered relation, so as to insure rigidity of the road bed structure as a whole.

The road bed when finished will present the appearance of a longitudinal center camber, flanked at each side by parallel ridges, and parallel ridges spaced from the first mentioned ridges and located at the remote edges of the road bed, with a smooth surface indicated at 1-1 in Fig. 1, upon which the wheels of vehicles are designed to travel. The slabs may be standarized so as to accommodate when laid vehicles of different transverse dimensions, but in a road bed having the proportions illustrated, the transverse distance between center to center of the smooth surfaces is 56 in., which will be found sufficient for all practical purposes. The road bed is intended to accommodate only a single file of vehicles, but if a road bed for vehicles traveling in both directions is desired, two systems of which the system herein described is a unit may be employed. Owing to the narrowness of this road bed, a road sufficient for many purposes may be quickly and economically laid, owing to the fact that the slabs may be manufactured elsewhere and in quantities, and brought to the place of their use where they may be quickly laid. The road presents a neat appearance, and the ridges at each side of the center tend to guide the wheels of a vehicle and prevent the same from leaving the road bed.

While I have illustrated and described my invention with some degree of particularity, I realize that in practice various alterations thereover may be made, and I therefore desire to reserve the right and privilege

of changing the form of the details of construction, or otherwise altering the arrangement of the correlated elements in the application of my process, without departing from the spirit of the invention, or the scope of the appended claims.

Having thus described my invention what I claim as new and desire to secure by Letters Patent is:

1. A road bed comprising spaced parallel longitudinal wheel receiving surfaces formed of slabs placed end to end, longitudinal reinforcing rods in the slabs extending partly into one another to maintain the slabs in alinement, means for connecting opposed slabs of the rows to maintain the gage, and a filling material between the rows.

2. A road bed comprising spaced parallel longitudinal wheel receiving surfaces formed of slabs placed end to end and slightly spaced from each other longitudinally, longitudinal reinforcing rods in the slabs extending partly into one another to maintain the slabs in alinement and permitting slight relative longitudinal movement thereof, means for connecting opposed slabs of the rows to maintain the gage, and a filling material between the rows.

3. A slab for use in constructing roadways, comprising a substantially rectangular slab of concrete, and longitudinally extending reinforcing rods embedded therein, the rods projecting at one end beyond the ends of the blocks and having their other ends bent at an angle and embedded in the block, said end of the block inclosing the bent ends of the rods having longitudinally extending recesses in alinement with the rods.

In testimony whereof I affix my signature in presence of two witnesses.

GEORGE N. HOFFMASTER.
